LINCOMYCIN HYDROCHLORIDE CRYSTALS
 Donald Ralph Van Overloop, Kalamazoo, Mich., assignor
 to The Upjohn Company, Kalamazoo, Mich., a corporation of Delaware
 No Drawing. Filed Aug. 30, 1963, Ser. No. 305,816
 1 Claim. (Cl. 167—65)

This invention relates to a new polymorph of lincomycin hydrochloride.

Lincomycin is a recently discovered antibiotic demonstrating pronounced activity against certain gram positive organisms, including especially *Staphylococcus aureus*, *Diplococcus pneumoniae*, and the beta hemolytic streptococci. The effectiveness of this antibiotic has been demonstrated in humans and animals against infections due to susceptible pathogens. However, administration of lincomycin hydrochloride in solid form has been complicated by the low density of this material as heretofore produced. For example, the preferred single dose of lincomycin hydrochloride of the known crystalline form, hereinafter designated polymorph I, requires administration either of a No. 00 capsule or two capsules of smaller sizes. The No. 00 capsule is generally regarded in the pharmaceutical industry as too large for human use and is only employed where it is particularly undesirable to present the medication in two smaller capsules constituting a single dose.

It has been unexpectedly found that a second crystalline form, or polymorph, of lincomycin hydrochloride can be produced which displays a significantly higher density and enables the single preferred dose to be incorporated in a No. 0 capsule. This size is generally regarded as acceptable in the industry and is widely employed.

Polymorph II displays a distinctive X-ray diffraction pattern, as indicated in the following comparison of interplanar spacings as obtained on X-ray diffraction of the two crystalline forms:

Interplanar spacings A

Polymorph I	Polymorph II	Polymorph I	Polymorph II
17.48 ¹	14.02	4.77	4.13
16.51	10.52	4.57	4.04
13.80	9.40	4.39	3.88
12.99 ¹	8.53	4.33	3.67

5.02	4.26	2.71	—

¹ Major peaks.

The General Electric XRD-5 spectrometer was used. (Cu radiation, 50 kvp., 16 ma., 2×Ni filter, 1° slit beam, MR soller, 0.2° detector slit, chart range linear 2000 c.p.s., 2° per minute scan, No. 6 SPG proportional counter 1.525 kv., gain 8, ΔE 6 volts, E 3 volts, time constant 1 second, target angle 3°.) Polymorph II is hygroscopic. Constant moisture content: 5.60%.

Polymorph I is characterized as light, bulky, needle-like crystals, whereas polymorph II exists as small, dense cubes. The solution rate of polymorph II in a test solution of 0.05 N hydrochloric acid is about 1½ times that of polymorph I.

Polymorph I is prepared by producing crystals through rapid addition of acetone to an aqueous solution of lincomycin hydrochloride at reduced temperature. Un-

2

expectedly, however, the advantageous polymorph II is formed when the acetone is added slowly and the temperature of the aqueous solution of lincomycin hydrochloride is maintained at or above about 25° C. Preparation of the lincomycin base and hydrochloride follows the methods described in Republic of South Africa Patent No. 2184/62, Belgian Patent No. 619,645 and U.S. Patent No. 3,086,912.

The following preparations and examples illustrate the production of the product of this invention and its pharmaceutical formulation but are not to be construed as limiting.

Example 1

15 Twenty-five gram aliquots of lincomycin hydrochloride were dissolved in 100 ml. of water and filtered through sintered glass. To one clarified aliquot was added 1500 ml. of acetone quickly and without stirring. The mixture was allowed to stand 3–5 minutes while maintained at 5–10° C., during which time crystallization took place. The crystals were removed by filtration, washed with acetone, and vacuum-dried at room temperature to give 22.1 gm. of lincomycin hydrochloride (polymorph I) characterized by the X-ray diffraction pattern given above.

20 To the other clarified aliquot from above was added 1000 ml. of acetone slowly (at a rate of 20–25 ml. per minute) and the mixture maintained at 30–35° C. with stirring. After stirring for four hours at that temperature, 25 the crystals were removed by filtration, washed with acetone and vacuum-dried at room temperature to give 18.1 gm. of lincomycin hydrochloride (polymorph II) characterized by the X-ray diffraction pattern given above.

Example 2—Capsules

25 Capsules of No. 0 size are the largest capsules in common use for human therapy. The No. 00 size (next larger) is generally regarded as too large for convenient administration. The standard single adult dose of lincomycin hydrochloride is 500 mg. for the majority of clinical indications.

30 Laboratory studies showed that a standard No. 0 capsule can contain only 420 mg. of the known polymorph I of lincomycin hydrochloride, whereas the standard No. 0 capsule can contain 520 mg. of the new polymorph II of lincomycin hydrochloride. The smallest capsule that will contain a single, 500 mg. dose of lincomycin hydrochloride polymorph I is the excessively large No. 00.

Example 3—Capsules

35 Hard filled capsules containing 250 mg. of lincomycin hydrochloride, polymorphs I and II, were prepared as follows on production capsulating machines.

(A) POLYMORPH I

60	Per Capsule (mg.)	Per 15,000 Capsules (gm.)
Lincomycin hydrochloride (Assay 900 meg./mg.)	278	4,170
Ethanol		595
Talc, bolted	15	225
Lactose U.S.P., bolted	75	1,125

40 In order to reduce the bulk of the drug, it was wetted with the ethanol, screened, dried and screened. Finally, it was mixed thoroughly with the talc and lactose and capsulated by machine. A No. 0 capsule was required.

3
(B) POLYMORPH II

	Per Capsule (mg.)	Per 15,000 Capsules (gm.)
Lincomycin hydrochloride (Assay 900 mcg./mg.)	278	4.170
Talc, bolted	15	.225
Lactose U.S.P., bolted	205	3.075
Magnesium stearate Po., U.S.P.	5	.75

The ingredients were mixed thoroughly and capsulated by machine. The smaller No. 1 capsule was adequate for this charge.

Thus polymorph II could be packed into a smaller hard filled capsule even though it contained three times as much lactose as filler (to increase flowability) and was not treated with ethanol to reduce bulk. The smaller No. 1 capsule can be swallowed more readily by most children.

What is claimed is:

A new polymorphic form of lincomycin hydrochloride,

4
the crystals of which are characterized by the following X-ray diffraction pattern:

Interplanar spacings, A

5	14.02 ¹	4.26
	10.52	4.13
	9.40	4.04
	8.53	3.88
	6.96	3.67
	6.19 ¹	3.50
10	5.90	3.45
	5.55	3.28
	5.34	3.02
	5.15	2.90
	5.01	2.76
15	4.62 ¹	2.57
	4.48	

¹ Major peaks.
